(57) **CLAIM**

The ornamental design of a water filter cartridge, as shown and described.

DESCRIPTION

FIG. 1 is a top, front, right side perspective view of a water filter cartridge showing my new design;
FIG. 2 is a depiction of the right portion of FIG. 1;
FIG. 3 is a front elevation view thereof;
FIG. 4 is a back elevation view thereof;
FIG. 5 is a right side elevation view thereof;
FIG. 6 is a left side elevation view thereof;
FIG. 7 is a top, back, left side perspective view thereof;
FIG. 8 is a top, back, right side perspective view thereof;
FIG. 9 is a depiction of the left portion of FIG. 8;
FIG. 10 is a top, front, left side perspective view thereof;
FIG. 11 is a bottom, back, left side perspective view thereof;
FIG. 12 is a bottom, back, right side perspective view thereof;
FIG. 13 is a depiction of the left portion of FIG. 12;
FIG. 14 is a bottom, front, left side perspective view thereof;
FIG. 15 is a bottom, front, right side perspective view thereof; and,
FIG. 16 is a depiction of the right portion of FIG. 15.
In the drawings, the dashed lines represent boundaries of the claim and form no part of the claimed design.

1 Claim, 15 Drawing Sheets
